UNITED STATES PATENT OFFICE.

KARL G. KARSTEN, OF NEW YORK, N. Y.

PACKAGE FOR DATES, FIGS, CANDIES, AND LIKE PRODUCTS.

Application filed February 17, 1922. Serial No. 537,165.

To all whom it may concern:

Be it known that I, KARL G. KARSTEN, a citizen of the United States, and resident of New York city, in the county of New York and State of New York, have invented certain new and useful Improvements in Packages for Dates, Figs, Candies, and Like Products, of which the following is a specification.

10 The invention relates to a method of assembling edible articles, such as dates, figs, bonbons, and like sticky articles, into a marketable package, and the invention also relates to the package as an article of manufacture suitable for store display and for table service.

The primary object of the invention is to provide a simple, easily practiced method for packaging sticky edible articles, and 20 which method will feature economy in labor and amount of material used.

Another object of the invention is to provide a package of dates or the like which will be attractive as a table dish and which 25 will permit the removal of the dates one at a time in serving the same, without materially uncovering or unnecessarily exposing or mutilating the remaining dates in the package.

30 Broadly, I attain these objects by assembling dates into a row, positioning the row in a flexible paper-like cup, surrounding the side of the cup with an endless row of dates to form a single layer, with their upper ends exposed, positioning the layer so formed in a second similar cup and repeating the addition of rows of dates until the desired size and shape of package is attained. Incidental to this assembling the sides and bottoms 35 of the cups will adhere to the dates due to the adhesive effect of their fruit sugars, thus causing the dates to form a unitary package even where the cups themselves are not secured to each other. A cover sheet is positioned on top of the layer and the package 40 thus formed is positioned in a suitable carton.

Considering the article feature of the disclosure, an object of the invention is to provide a simple, easily constructed paper or 50 paper-like package from which the individual dates may be removed, after tearing off the top cover sheet and without further necessity of tearing the package or handling 55 sticky or messy paper.

Still another object of the article feature

of the disclosure is to provide a simple package of the type outlined, which is susceptible of being formed into different shapes and sizes so as to fit in conventional 60 forms of cartons.

Various other features and advantages of the invention will be in part obvious from an inspection of the accompanying drawings and in part will be more fully set forth in the following particular description of one form of mechanism embodying my invention, and the invention also consists in certain new and novel features of construction and combination of parts hereinafter set 70 forth and claimed.

In the accompanying drawings:—

Figure 1 is a plan view looking down on a preferred embodiment of the invention;

Figure 2 is a reduced perspective view of 75 the package shown in Figure 1 and with some of the dates removed; and

Figure 3 is a vertical sectional view taken on the line 3—3 of Figure 1.

In the drawings there is shown a package of dates comprising an inner row A contained in an open top elongated cup 10 having an upstanding continuous side 11 surrounding the innermost row of dates. A second endless row B of dates encircles the 80 side 11 so that the side forms an endless partition between the rows of dates thus separating the rows. A cup 12 of the necessary larger area to accommodate the circle 85 row B surrounds the same and the sides 13 of the cup 12 forms another concentrically disposed partition. Any number of additional rows may be added to form a flat 90 layer of dates and for an illustration of one such additional row reference is made to the outer row C in the drawings. The layer including the rows A, B, C and cups 10, and 95 12 are contained in an outer cup 14 which includes a bottom 15 and a continuous side 16 integral with the bottom. The package 100 may include a cover sheet 17 and a bottom sheet or doily 18.

It is suggested that the cups be free of each other, but are preferably stuck together with glue, in which case the bottoms 105 of the inner cups may be cut away to minimize extra thickness of material in the bottom of the package.

The cups are each preferably made of a single sheet of flexible paper such as wax paper or colored glasseine, and are preferably die-stamped to give a lace-like decora- 110

tive pattern. They may be crinkled or pleated along the sides so as to cause the sides to extend approximately at right angles to each other and otherwise to engage 5 and closely adhere to the sides of the dates.

In dispensing the dates from the illustrated package, it is merely necessary to bend down a part of the outermost side or partition thus exposing one or more of the 10 dates in the outermost layer. One of the exposed dates is removed by engaging its upper edge and pulling it away from the adjacent dates and the bent down side or partition is then turned back in place or left 15 in its bent down position to facilitate access to the next adjacent date in the row. When all of the dates have been removed from the outermost row its outer portion will be opened out, laying flat on the dish 20 and by bending down the next partition access is similarly provided to the next adjacent inner row of dates, and so on until all of the dates in the package are removed.

Until the last date is eaten and the whole 25 lot of paper is to be thrown away, there are no stray or loose pieces of paper laying about. To the last the paper remains on the plate about the dates protecting them on

all sides, except on one end and not in the way to interfere with their removal from 30 the package.

Having thus described my invention, I claim:

1. A package for more than two parallel rows of articles intended to be separated one 35 at a time from the package, said package comprising a plurality of open top cups, disposed one within the other in telescoping relation, each succeeding outer cup having a greater area when considered in plan than the next adjacent inner cup thereby to provide a space between the sides of adjacent cups to accommodate an endless line of the articles and the innermost cup adapted to contain a single row of the article. 40

2. A device of the class described, comprising a plurality of paper-like, flat bottom cups telescoping one within the other and with the bottom of one resting on the bottom of another, the sides of said cups 50 being spaced apart to provide article containing spaces therebetween. 45

Signed at New York city, in the county of New York and State of New York, this 20th day of January, A. D. 1922.

KARL G. KARSTEN.
